EASEL

Vincent Fortunato, Brooklyn, N. Y., assignor to
The Mounting & Finishing Co. Inc., Brooklyn,
N. Y.

Application October 12, 1938, Serial No. 234,567

9 Claims. (Cl. 40—152.1)

This invention relates to easels, and more particularly to folding easels for offset cardboard display units.

The principal object of the invention resides in an easel which may be flatly folded against the rear side of an offset foldable display unit when the latter is in unfolded flat condition to facilitate compact storing and shipment of the display units to their destinations for use, where they are intended to be set up for display purposes.

Another feature of the invention is to provide a foldable easel for display units having offset panel sections, which easel may be easily set up for use, and which braces and rigidly supports the offset panels of the display unit in an upright position.

Other features of the invention will be apparent as the following specification is read in conjunction with the accompanying drawings, in which:

Figure 1 is a perspective view of an offset display unit in a set up position and equipped with a single prop easel constructed in accordance with my invention.

Figure 2 is a side elevational view.

Figure 3 is a horizontal sectional view on the line 3—3 of Figure 2.

Figure 4 is a rear elevational view showing the display unit and easel in flat unfolded position.

Figure 5 is a perspective view of the single prop easel associated with a modified form of offset display unit, the same being in flat unfolded position.

Figure 6 is a rear elevational view of a display unit equipped with a double prop easel, the parts being shown in flat unfolded position.

Figure 7 is a rear elevational view of the display unit shown in Figure 6 with the parts in folded set up position.

Figure 8 is a side elevational view.

Referring to the drawings by reference characters, the numeral 10 designates my improved cardboard display unit in its entirety which includes a single sheet of stiff cardboard A scored on spaced parallel horizontal lines 11 and 12 which are disposed parallel to the straight bottom edge 13 of the sheet to divide the same into a lower panel section 14, an upper panel section 15, and an intermediate section 16. The cut of the score line 11 is made on the front of the sheet A and the score line 12 on the rear side thereof so that the sheet may be easily folded to a position to cause the panels 14 and 15 to

assume an offset position when the display unit is in set up position. The front side of the panel sections 14 and 15 are intended to have any desired display or indicia printed thereon.

My improved easel is designated by the numeral 17 and is formed from a single blank of stiff cardboard scored lengthwise on the broken longitudinal hinge fold line 18 to divide the blank into an attaching flap 19 and a hinged prop 20. The prop 20 is of substantially triangular shape 10 and includes a straight base edge 21 and a straight side edge 22 which converges toward the top end of the hinge fold line 18. The attaching flap 19 is notched inwardly from its free side edge as at 23 which provides straight opposed shoulders 24 and 25, the same being parallel to and disposed in the same plane with the respective score lines 11 and 12 when the easel is flat against the rear side of the display panels as best illustrated in Figure 4 of the drawings. The inner end of the notch terminates in a straight vertical edge 26 which is disposed in alignment with the hinge fold line 18. The height of the notch 23 is equal to the width of the intermediate panel section 16 and is of a depth equal to the width of the attaching flap 19. The attaching flap 19 is adhesively secured to the rear side of the panel sections 14 and 15 at right angle to the score lines 11 and 12 and skipping the intermediate section 16 due to the notch 23.

The prop 20 is divided by spaced parallel angular score lines 27 and 28 into an upper prop section 29 and a lower prop section 30, the material between the score lines constituting a foldable intermediate section or web 31. The score 35 27 is cut from the inner side of the prop and the score 28 is cut from the outer side thereof so that the lower prop section 30 will fold up against the right side of the upper prop section 29 when the easel is folded for use as shown in Figures 1 to 3. 40 However, the cutting of the score lines 27 and 28 may be reversed to cause the lower prop section 30 to fold up against the left side of the upper prop section 29 as shown in Figures 7 and 8 without in any way effecting the desired result. The inner end of the web 31 is cut free of the lower prop section 30 on the same plane as the shoulder 24 to provide a continuation shoulder portion 32 on which the intermediate panel section 16 rests when the display unit is folded 50 and set up for use.

Cut from a portion of the upper panel section 29 and an adjacent portion of the attaching strip 19 is a locking tongue 33, the same being foldable outwardly and downwardly on 55

the horizontal fold line 34. The free end of the tongue 33 is provided with a slot 35 of a width to receive three thicknesses of the material from which the prop is constructed in a manner to be presently described and as clearly shown in Figure 3. The wall of the opening in the upper prop section formed by the cutting of a portion of the tongue 33 therefrom is formed with a stop shoulder 36 and an adjacent notch 37 into which the end wall of the slot 35 is forced into interlocking engagement when the parts are folded into locking relation.

For setting up the display unit 10 from its flat folded position shown in Figure 4 to the position shown in Figures 1 and 2, the operator first swings the prop 20 outwardly on the hinge fold line 18 to a position at right angle to the rear side of the flat display panels; secondly, the operator applies opposite forces to the free ends 20 of the upper panel section 15 and lower panel section 14, causing the same to fold on the lines 11 and 12 which offsets the two panel sections relative to each other and provides a stepped horizontal intermediate section 16. As the sections 14 and 15 move toward each other to offset position, the upper and lower prop sections 29 and 30 move a corresponding distance relative to each other which is compensated for by reason of the folding web connection 31, which 30 web connection folds upwardly on the angular fold lines 21 and 28. Thirdly, the operator folds the locking tongue 33 outwardly and downwardly causing the three plies of material, namely the web 31 and adjacent lapping portions of the 35 upper and lower prop sections 29 and 30 to enter the slot 35 with the opposite walls of the slot embracing the prop sections. The tongue 33 is limited in its outward and downward swinging movement by its engagement with the stop shoulder 36 and is held against accidental movement by reason of the interlocking of the free edge of the tongue in the notch 37. The connecting panel section 16 now assumes a horizontal position and rests upon the shoulder 32, with 40 the upper panel section 15 stepped back relative to the lower panel section 14 when looking at the front of the display unit. Stepped back display panels are resorted to in display signs wherein the appearance of depth or the third 45 dimension is desired, and it will be appreciated that with the easel locked in its perpendicular position at right angle to the rear surface of the display panel, that a rigid stepped back display unit is provided.

Should it be desired to unfold the set up display unit into flat condition, the locking tongue 33 is swung up against the upper panel section 15, and the sections 14 and 15 pulled away from each other which causes the same to move 50 into the same plane and simultaneously unfolds the web 31 and swings the prop 20 to a position flat against the display panel sections.

In Figures 5 to 8 inclusive I have illustrated a modified form of display panel wherein the lower panel section 14 is provided with side flaps 38-38 which fold rearwardly on the score lines 39-39 which are in alignment with the ends of the intermediate panel section 16. The upper or inner ends of the flaps 38-38 are provided with notches 40 and finger portions 41. The sides of the upper panel section 15 are provided with extension portions 42-42, the lower or inner ends of which are provided with notches 43. Before the upper and lower panel sections are shifted to offset display position,

the flaps 38-38 are folded back to a position at right angle to the lower panel section, and as the panel sections shift inwardly the notches 40 of the flaps fit into the respective notches 43 and the walls thereof interfit to retain said flaps in rearwardly extending position to close in the opposite sides of the lower panel section. The fingers 41-41 extend upwardly and brace the upper panel section 15 directly above the fold line 12. After the flaps 38 are locked in the manner described, side flaps 44-44 on the extension portions 42-42 are folded rearwardly on the fold lines 45-45 to close in the sides of the upper panel section 15.

The easel shown in Figure 5 is identical to that shown at 17 in Figures 1 to 4 inclusive, and like reference characters refer to corresponding parts. However, the easel shown in Figures 6 to 8 inclusive is similar to the easel 17 but is of the double prop type. The double prop 20 easel is designated in its entirety by the numeral 50 and is formed from a single blank of cardboard to provide a central attaching strip 51 adhesively secured to the rear of the panel sections 14 and 15, foldable props 52-52 at opposite sides thereof, and a single locking flap 53 equivalent to the locking flap 33 but which differs therefrom in that it has two notches 54-54 instead of the one notch 35. The props 52 are identical in construction to the prop 20 heretofore described and each is divided by spaced angular fold lines 55 and 56 into an upper prop section 57, a lower prop section 58, and an intermediate folding web connection 59. The scores forming the fold lines 55 and 56 are made 35 to cause the web connections 59 to fold up against the inner sides of the upper panel sections 57 when the display unit is set up for use as shown in Figure 7 of the drawings. The easel blank is cut away as at 60 to provide the necessary gap 40 in the attaching strip equivalent to the notch 23 and which provides shoulders 61-61 on which the intermediate panel section 16 rests. This form of easel is unfolded in the same manner as the easel 17 with the exception that the two 45 props 52-52 are swung outward to spaced parallel position, after which the upper and lower panels are shifted to offset position causing the web connections to break upward, after which the tongue 53 is folded outwardly and downwardly on the fold line 62 and the notches 54 receive the respective folded webs and related prop sections. The double locking tongue 53 abuts shoulders 63 on the respective props, and the end walls of the notches 54-54 interlock 55 in notches 64-64 which are formed in the props adjacent the stop shoulders 54-54.

The double prop easel 50 may be said to be formed of two props similar to the single prop 17, and the two props held locked by the single 60 double notched flap 53. Aside from this slight difference in construction the single and double prop easels are identical and it is not believed necessary to further discuss the construction and function of the double prop easel 50. The double 65 prop easel will be found useful in relatively large display units wherein a single prop would not provide the desired rigid support.

In Figures 5 to 8, the bottom edge of the easel is cut at an angle with respect to the 70 bottom straight edge of the lower panel section so that when the easel is set up, the display panels will assume a slightly backward tilted position, instead of the substantially vertical position shown in Figures 1 and 2.

While I have shown and described what I consider to be the most practical embodiment of my invention, I wish it to be understood that such changes and alterations as come within 5 the scope of the appended claims may be resorted to if desired without in any way departing from the spirit of the invention.

Having thus described the invention, what I claim as new and desire to secure by Letters 10 Patent of the United States, is:

1. A cardboard display unit comprising a foldable offset display panel formed from a single piece of cardboard and normally flat and shiftable into offset set up position to provide an upper panel section, a lower panel section, and an intermediate panel section; an easel attached to the rear of the offset upper and lower panel sections and normally foldable flat thereagainst, said easel including a hinged prop swingable to a set up position at right angle to said display panel, foldable means integral with said prop and normally disposed in flat unfolded condition against said display panel and adapted to be folded to compensate for the relative shifting of the upper and lower panel sections to offset position, and a means formed from said easel for locking the foldable means in folded position when moved thereto by the shifting of said display panel to offset position.
2. A cardboard display unit comprising a foldable offset display panel formed from a single piece of cardboard and normally flat and shiftable into offset set up position to provide an upper panel section, a lower panel section, and an intermediate panel section; an easel attached to the rear of the offset upper and lower panel sections and normally folded flat thereagainst, said easel including a hinged prop swingable to a set up position at right angle to said display panel, foldable means integral with said prop and normally disposed in flat unfolded condition against said display panel and adapted to be folded to compensate for the relative shifting of the upper and lower panel sections to offset position, and a locking tongue hinged to the rear of said panel and adapted to interlock with the folded means when the panel is shifted to offset position to secure the prop in locked supporting position.
3. A cardboard display unit comprising a display panel scored horizontally on spaced parallel lines to divide the same into a lower panel section, an upper panel section and an intermediate panel section, the sections of said display panel being normally flat and disposed in the same plane and foldable on the parallel score lines to cause the upper and lower panel sections to assume offset planes, an easel secured to the rear of said upper and lower panel sections including a hinged prop normally disposed in a position flat against the rear of said display panel and swingable to a position at right angle thereto, foldable lapping means formed integral with said prop for compensating for the relative movement of said upper and lower panel sections to offset planes, and a locking tongue flap hinged to the rear of said upper panel section and having a notch therein for receiving and holding the foldable lapping means against unfolding.
4. A cardboard display unit comprising a display panel scored horizontally on spaced parallel lines to divide the same into a lower panel section, an upper panel section and an intermediate panel section, the sections of said dis-

play panel being normally flat and disposed in the same plane and foldable on the parallel score lines to cause the upper and lower panel sections to assume offset planes, an easel secured to the rear of said upper and lower panel sections including a hinged prop normally disposed in a position flat against the rear of said display panel and swingable to a set up position at right angle thereto, said prop being scored on two spaced parallel lines to divide the same 10 into an upper prop section, a lower prop section, and a folding intermediate section, whereby folding of said display panel to offset the upper and lower display panels will cause said intermediate prop section to fold into lapping 15 relation with respect to the upper and lower prop sections, and releasable locking means engageable with the folded intermediate prop section for securing the same in folded position.

5. A cardboard display unit comprising a display panel scored horizontally on spaced parallel lines to divide the same into a lower panel section, an upper panel section and an intermediate panel section, said display panel being normally flat and foldable on the parallel score lines to 20 cause the upper and lower panel sections to assume offset planes, an easel secured to the rear of said upper and lower panel sections including a hinged prop normally disposed flat against the rear of said display panel and swingable to a position at right angle thereto, said prop being scored on two spaced parallel lines extending angularly thereacross to divide the same into an upper prop section, a lower prop section, and a folding intermediate section, whereby folding 30 of said display panel to offset the upper and lower display panels will cause said intermediate prop section to fold into lapping relation with respect to the upper and lower prop sections, and a hinged locking tongue flap formed from said 35 easel and having a notch therein to receive and hold the lapping portions of said upper and lower prop sections with the intermediate folded section therebetween.

6. A cardboard display unit constructed in accordance with claim 5, and including releasable interlocking means between said tongue prop and the upper flap section.

7. A cardboard display unit comprising a foldable display panel having a lower panel section, an upper panel section stepped back from said lower panel section, and an intermediate step section connecting said lower and upper panel sections; an easel including a single blank of stiff cardboard cut and scored to provide spaced 50 attaching flap sections adhesively secured to the rear of said lower and upper panel sections, a hinged prop connected to said attaching flap sections, spaced parallel fold lines extending angularly across said prop and dividing the same 55 into a lower prop section, an upper prop section, and intermediate folding web section, said prop extending outwardly from the rear of said display panel with the inner ends of said prop sections lapping the folded web section, and a locking 60 tongue flap formed from the easel blank and having a notch for receiving the folded inner ends of the upper and lower prop sections with the web section folded therebetween.

8. A cardboard display unit comprising a foldable display panel having a lower panel section, an upper panel section stepped back from said lower panel section, and an intermediate step section connecting said lower and upper panel sections; an easel including a single blank of stiff 70

- cardboard cut and scored to provide spaced attaching flap sections adhesively secured to the rear of said lower and upper panel sections, a hinged prop connected to said attaching flap sections, spaced parallel fold lines extending angularly across said prop and dividing the same into a lower prop section, an upper prop section, and an intermediate folding web section, said prop extending outwardly from the rear of said display panel with the inner ends of said prop sectionslapping the folded web section, a shoulder formed on said lower prop section and underlying the intermediate step section of the display panel and on which the step section rests, and a locking tongue flap formed from the easel blank and having a notch for receiving the folded inner ends of the upper and lower prop sections with the web section folded therebetween.
9. A cardboard display unit comprising a foldable display panel having a lower panel section, an upper panel section stepped back from said

lower panel section, and an intermediate step section connecting said lower and upper panel sections; an easel including a pair of alined attaching strip sections respectively secured to the rear of the panel sections, a pair of props hinged to opposite sides of said attaching strip sections, each of said props being provided with spaced parallel fold lines extending angularly across the same to divide the prop into a lower prop section, an upper prop section, and an intermediate folding web section, said props extending outwardly from said display panel in substantially spaced parallel relation with the web sections folded and the inner ends of the related lower and upper prop sections overlapping the same, and a single locking tongue hinged to the rear of the upper panel section and having a pair of spaced notches therein for respectively receiving the lapped folded portions of the two props to lock the same in folded set up position. 20

VINCENT FORTUNATO.
